TRAFFIC SIGNAL

Willem Huizinga, Amsterdam, Netherlands

Application February 13, 1930, Serial No. 428,146,
and in the Netherlands February 13, 1929

5 Claims. (Cl. 177—337)

The invention relates to a device for controlling traffic, more particularly street traffic, by means of one or more colored surfaces, each of which is lighted at intervals.

5 The advantage of such a device is that the signal device itself presents to the traffic an indication of its duration and of the time at which it will change.

The invention relates more particularly to a device by means of which the above object can be realized in a very practical and simple manner, and moreover to a device which from a technical point of view has special advantages.

10 In the first place, the invention comprises lighting a number of colored surfaces and successively extinguishing the sources of light or the groups of sources of light.

The device may comprise a casing suspended or placed upon a pedestal or column, or arranged in 20 any other manner, and a number of sources of light, e. g., electric lamps, arranged in said casing or on said pedestal in such a manner that in case said lamps have been lit a surface or field of a certain color is visible. These lamps are connected, either separately or in groups, with a switching device that causes the lamps of a particular colored signal to be lit all together and to be extinguished in succession or in successive groups.

25 The device may comprise one or more of such fields of different colors, e. g., for giving a red signal for stopping and a green one for proceeding.

The switching device may comprise a rotating controller drum, such as often used for electrical advertisement and the like. One switching device 35 may be used for a plurality of apparatus. This switching device may be operated manually, electrically, or mechanically.

In order to obtain the desired color effect, use 40 may be made of lamps with colored glass bulb, or of colored transparent windows (colored glass), or any other device for producing colored light. Neon lights may be utilized advantageously.

In order to get a surface or field which is colored 45 as equally as possible, it may be advisable to employ a screen of ground glass, milk glass, or other transparent light-diffusive glass. In such a case, partition walls may be arranged between the sources of light in such a manner that the screen before the extinguished lamps receives no light or 50 very little light.

It is further observed that the connection between the sources of light and the switching device, and also the switching device itself, may differ very much. The arrangement may be such 55 that all lamps of one color are lit at the same time

and extinguished one after the other, and likewise groups of lamps may be extinguished in succession.

Further, the sequence in which the lamps or the groups of lamps are extinguished may vary, and likewise the manner in which these groups are arranged with respect to each other may be varied.

The invention further relates to an improvement of devices as described hereabove, and in general to devices by means of which traffic may 65 be controlled with the aid of a number of differently colored and alternately appearing lights. In my invention, the colored surfaces appear substantially in the same plane.

It is evident that the signal control by this 70 method results in smoother and more efficient traffic flow, because the driver of the vehicle need only turn his eye towards one certain point. Furthermore, the device looks small and simple, which 75 qualities are essential to traffic control purposes.

This invention may be realized in many ways. Thus, the sources of light for producing two colors (e. g., red and green) may be arranged alternately, and the whole may be set behind a screen of 80 ground glass, milk glass, or other light-diffusive substance. The arrangement should be such that the sources of light for one color do not interfere with those for the other color.

For the purposes of my invention, neon tubes 85 are especially effective, because they do not need colored transparent windows. The tubes for both colors, or for a plurality of colors, may be arranged alternately, and the connection may be such that the tubes for producing one color, after being lit, may be extinguished one after the other, whereupon the same operation occurs with the tubes for the other color.

The sources of light or the tubes may be arranged in any position with respect to each other, 95 while the connection, i. e., the sequence in which they are extinguished, may also be different. So the sources of light may for example be placed in concentric circles and the neon tubes may consist of concentric circular tubes. The device may 100 work in combination with others for different crossings, and they may also be combined with signal control devices for pedestrians.

Signal devices according to the invention may be provided in a simple manner with means by 105 which in case of need all signals may be placed manually, and/or automatically, for example, in order to pass the fire engines, street cars, or processions, or in case of accident. This makes it possible to find a solution for giving some pref- 110

erence to the street car traffic, which manner of controlling may be automatic by closing or interrupting contacts by the street car before the crossing in question.

5 The invention is more fully described by the drawings, which show one embodiment of a traffic control device according to my invention.

10 Figure 1 is a vertical, schematic section of a signal apparatus according to the invention.

15 Fig. 2 is a front view of the indication apparatus.

Fig. 3 shows schematically the diagram of connections for switching in and off the light sources.

15 The apparatus comprises a cylindrical casing 1, constructed of durable material such as iron and having a diameter of about 60 centimeters. The front of this casing is provided with a glass screen 2 or the like, and the back with a detachable plate 3. At some distance from the casing wall, a disk 4 is arranged within the casing, said disk being made preferably of multiplex-wood or similar material, containing several perforations or openings and connected with the casing 1 by means of supports 16. Nine neon tubes 5—13 which are circularly bent and nest within one another are mounted on the said wooden disk 4. The odd numbered tubes may radiate a red light, and the even numbered tubes a green light.

20 30 The electrodes of said tubes 5—13 pass through the perforations in the wooden disk 4 and thus they are arranged in the space which is accessible by means of the partition wall 3. The high voltage cables 14 connecting the various electrodes with the switching device enter into the said space.

25 On the front of casing 1, a screen 15 is arranged at the top in order to block out daylight and sunlight, so that the light signals will be clearly visible. The complete apparatus may be arranged on a pedestal 17 or against a wall by means of supports or be suspended from cables.

30 45 Fig. 3 illustrates the diagram of connection of the device for lighting and extinguishing the neon tubes. The device comprises a controller drum 18 for short circuiting and lighting the neon tubes and contacts 19 sliding over said drum. These contacts 19 are connected with the high-voltage cables 14. The controller drum 18 is driven, via 50 a reducing coupling 20, by an electromotor 21 having a predetermined number of revolutions which may be adjustable. The electromotor 21 is connected with the power network by the conductor 22 via fuses 23 and a switch 24. The frame of the controller drum, the motor, and the 55 transformers 25 and 26 are connected to ground, as is also one of the contacts 19. The available voltage (of 220 volts, for example) is stepped up by the transformers, which are connected in parallel, to the voltage necessary for lighting the neon tubes (such as 3500 volts). The transformers 25 and 26 are also connected in series with the neon tubes, so that for extinguishing the tubes it is necessary to only short circuit the latter. The advantage of this is that sparking on the controller drum 18 is considerably less than would be the case if the neon tubes were switched off. In this manner, the life of the controller 60 drum and the corresponding contacts is increased, since said parts are less subject to burning. Moreover, the transformers may be considerably smaller, which is an advantage when the available space is small.

65 70 75 75 When the controller drum 18 rotates, the contacts 19 slide over the drum in such a manner, that with the exception of one contact, they come into contact with the body 18 of the drum or are out of contact with the said body. As soon as a contact comes in engagement with the body 18, one of the neon tubes is short circuited, and this short circuit is disconnected only when the said contact is broken. One of the contacts 19 which is connected to ground is in a continuous connection with the body of the drum.

80 85 90 95 100 105 110 115 120 125 130 135 140 145 150

According to the illustrated embodiment, the controller drum is constructed so that when it is in rotation, at first the five left contacts 19 cause the short circuit of five tubes (for example, the five tubes giving green light). At this moment, the four right contacts 19 are out of contact with the body 18, so that the other four tubes (e. g., the four tubes giving red light) are in operation. As the drum continues its rotation, the four right contacts are short circuited in succession, so that the corresponding four tubes are extinguished in succession. As soon as the last (inner) tube giving red light has been extinguished, the short circuit on the tubes giving green light is raised because the connection of the five left contacts is broken and the green tubes will light. After some time, the tubes giving green light are short circuited one after another, and immediately thereupon the tubes giving red light begin to light again. At this moment, the drum has performed one revolution.

The transformers should be able to bear the short circuit on the tubes and are calculated so that they can endure the total short circuit.

The controller drum 18 may be constructed so that the duration of the short circuit and that of the lighting of the tubes are mutually and independently adjustable. This may be effected, for example, by constructing the drum of some 110 adjustably arranged rings, the number of which corresponds with the number of tubes or groups of tubes. Moreover, the contacts may be adjustably arranged on the said drum so that any variation is possible.

The present invention also contemplates a 120 signal which has only one light radiating surface, usually red. In this case, all of the concentric neon tubes shown in Fig. 2 will radiate red light. After they are all lit, they are gradually extinguished one at a time by means of the controller 125 drum 18. It will be obvious that in this instance the controller drum 18 will differ from that shown in Fig. 3. In Fig. 3, it is necessary to light half the tubes and to extinguish them gradually, and thereafter to light the other half of the tubes and 130 to extinguish them gradually. The controller drum in this instance should have a continuous group of contacts in the form of steps. In the lowermost position, all the tubes are short circuited so that the traffic signal does not show any 135 light, and the traffic moves unhindered. In the next higher position, all the tubes will show a red light so that the traffic is stopped. In the next higher position, one of the tubes is short circuited so that the total amount of surface 140 illuminated red becomes smaller. This keeps on until the last or the uppermost position, as shown on the drum 18, when all the tubes are short circuited again, and the light radiating surface has disappeared. In the meantime, of course, the 145 operators of the vehicle have been informed of the duration of the signal by the amount of illuminated surface visible to them.

If it is desired to control the signal manually, the controller drum 18 may be manually moved 150

so that the proper tubes or number of tubes are short circuited. This can be very easily done by having indexes on the controller drum to enable the operator of the device to quickly move the drum into the desired position. If it is desired to have the traffic controlled by street cars, the street car rail may have a contact which is closed by the car wheel to halt traffic opposing the street car. Other modifications will be apparent to those skilled in the art.

The embodiment as described above is not intended to restrict the invention to the use of only two colors. If only one color (e. g., a stopping signal) is desired, or in case use is made of more colors (e. g., in case of an intermediate color between red and green), the invention can be applied with the same advantages.

I claim:—

1. In a traffic signal, a group of gaseous discharge tubes of one color, a group of gaseous discharge tubes of a different color, means for mounting said groups concentrically with a tube of one color alternating with a tube of a different color, a source of energy, and means for applying said source of energy to one entire group of tubes and then extinguishing the last said tubes one at a time.
2. In a traffic signal, a group of gaseous discharge tubes of one color, a group of gaseous discharge tubes of a different color, means for mounting said groups concentrically with a tube of one color alternating with a tube of a different color, a source of energy, and means for

applying said source of energy to one entire group of tubes and then extinguishing the last said tubes one at a time, the last-named means applying the source of energy to the second entire group of tubes after the last tube of the first group has been extinguished.

3. In a traffic signal, a plurality of groups of gaseous discharge tubes, each group comprising a different color, means for mounting said groups with a tube of one color alternating with tubes of different color, a source of energy, means for applying said source of energy to one entire group of tubes and then extinguishing the tubes of said groups one at a time, and means for applying said source of energy to another entire group of tubes when the last tube of the preceding group has been extinguished.

4. In a traffic signal, a group of gaseous discharge tubes adapted to emit the same color concentrically mounted, a source of energy, and means for applying said source of energy to the entire group of tubes and then extinguishing the tubes one at a time.

5. In a traffic signal, a group of substantially circular neon gaseous discharge tubes adapted to emit the same color of varying sizes concentrically mounted, and means for supplying all of the discharge tubes with electrical energy at the same time and for successively discontinuing said supply of energy to the tubes one at a time.
